UNITED STATES PATENT OFFICE.

WILLIAM H. PORTER, OF WASHINGTON, DISTRICT OF COLUMBIA, ASSIGNOR
OF TWO-THIRDS TO CHARLES W. SCHNEIDER AND CLARENCE BAKER,
OF SAME PLACE.

APPLIANCE FOR PREVENTING INCRUSTATION.

SPECIFICATION forming part of Letters Patent No. 425,903, dated April 15, 1890.

Application filed July 20, 1889. Serial No. 318,176. (No model.)

To all whom it may concern:

Be it known that I, WILLIAM H. PORTER, of Washington, District of Columbia, have invented a certain new and Useful Appliance 5 for Preventing Incrustation of Steam-Boilers, of which the following is a specification, reference being had to the accompanying drawing.

The object of my invention is to provide 10 for the use of a permanent magnet within a steam-boiler in such a way as to prevent its incrustation or to remove scale when formed. To this end I employ a permanent magnet within the boiler and connect it by its ends 15 or poles preferably to the flues of the boiler, but always to some part below the water-line.

The drawing is a perspective view illustrating my invention applied to an ordinary steam-boiler having flues.

20 A is the shell of the boiler, B the flues, and C the permanent magnet, preferably of usual horseshoe form.

In practice I have found that a permanent

magnet applied in a boiler in this way and connected by both of its ends to the flues or 25 lower part of the boiler under water serves the purpose of preventing incrustation admirably. The heat of the water can never be sufficient to disturb the efficient action of the magnet when magnetized so as to be of sufficient strength. By using a permanent magnet 30 in this way very little room is taken up within the shell of the boiler, and the magnet can readily be removed and replaced, if required.

What I claim is—

35 The combination, with a steam-boiler, of a permanent magnet applied within the boiler, so that its ends or poles shall be in contact with the lower part of the boiler or its flues under water, substantially as set forth.

40 In testimony of all which I have hereunto subscribed my name.

WILLIAM H. PORTER.
